(57) **CLAIM**

The ornamental design for a susceptor tray, as shown and described.

DESCRIPTION

FIG. 1 is a perspective view of a susceptor tray showing the new design;

FIG. 2 is a side elevational view thereof, the opposite side elevational view being the same as FIG. 2;

FIG. 3 is a top plan view thereof;

FIG. 4 is a bottom plan view thereof;

FIG. 5 is a longitudinal sectional view thereof;

FIG. 6 is a perspective view of a second embodiment of the susceptor tray;

FIG. 7 is a side elevational view thereof, the opposite side elevational view being the same as FIG. 7;

FIG. 8 is a top plan view thereof;

FIG. 9 is a bottom plan view thereof; and

FIG. 10 is a longitudinal sectional view thereof;

FIG. 11 is a perspective view of a third embodiment of the susceptor tray;

FIG. 12 is a side elevational view thereof, the opposite side elevational view being the same as FIG. 12;

FIG. 13 is a top plan view thereof;

FIG. 14 is a bottom plan view thereof;

FIG. 15 is a longitudinal sectional view thereof;

FIG. 16 is a perspective view of a fourth embodiment of the susceptor tray;

FIG. 17 is a side elevational view thereof, the opposite side elevational view being the same as FIG. 17;

FIG. 18 is a top plan view thereof;

FIG. 19 is a bottom plan view thereof; and,

FIG. 20 is a longitudinal sectional view thereof.
